UNITED STATES PATENT OFFICE

EDWARD S. PRESTON, OF CHICAGO, ILLINOIS, ASSIGNOR TO CHICAGO ELECTRIC MANUFACTURING CO., OF CHICAGO, ILLINOIS, A CORPORATION OF ILLINOIS

DESIGN FOR A CASING FOR AN ELECTRIC TOASTER OR LAMP

Application filed January 23, 1931. Serial No. 38,419. Term of patent 7 years.

To all whom it may concern:

Be it known that I, EDWARD S. PRESTON, a citizen of the United States, residing at Chicago, in the county of Cook and State of Illinois, have invented a new, original, and ornamental Design for a Casing for an Electric Toaster or Lamp, of which the following is a specification, reference being had to the accompanying drawing, forming part thereof.

In the drawing, the figure is a perspective

view of an electric toaster or lamp, showing my new design, the opposite end and opposite side of the casing being respectively counterparts of the end and side shown in the drawing.

I claim:

The ornamental design for a casing for an electric toaster or lamp, substantially as shown and described.

EDWARD S. PRESTON.
